UNITED STATES PATENT OFFICE

111,197

DESIGN FOR A DOUGH MIXING MACHINE OR SIMILAR ARTICLE

Walter F. Dehuff, Glen Rock, Pa., assignor to
American Machine & Foundry Company, a cor-
poration of New Jersey

Application December 16, 1937, Serial No. 73,660

Term of patent 14 years

To all whom it may concern:

Be it known that I, Walter F. Dehuff, a citizen
of the United States, residing at Glen Rock, in
the county of York and State of Pennsylvania,
have invented a new, original, and ornamental
Design for a Dough Mixing Machine or Similar
Article, of which the following is a specification,
reference being had to the accompanying draw-
ings, forming part thereof.

Fig. 1 is a front perspective view of the dough
mixing machine or similar article, showing my

new design; Fig. 2 is a rear perspective view
thereof; and Fig. 3 is a front perspective view,
showing the same machine from a different view-
point, with the head thereof in an elevated posi-
tion.

I claim:

The ornamental design for a dough mixing
machine or similar article, as shown and de-
scribed.

WALTER F. DEHUFF.
